UNITED STATES PATENT OFFICE.

WILLIAM E. BEAKES, OF BRANT ROCK, MASSACHUSETTS, ASSIGNOR, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

DETECTOR FOR OSCILLATING CURRENTS.

1,158,112.

Specification of Letters Patent.

Patented Oct. 26, 1915.

Application filed May 9, 1911. Serial No. 626,073.

To all whom it may concern:

Be it known that I, WILLIAM E. BEAKES, a citizen of the United States, residing at Brant Rock, in the State of Massachusetts, 5 have invented certain new and useful Improvements in Detectors for Oscillating Currents.

My invention relates more particularly to wireless telegraph receivers of the good contact type, and comprises the discovery of a material having great advantages for indicating the presence of oscillating currents, together with the best means of associating the same with circuits.

15 I have illustrated the invention in the accompanying drawing, in which—

Figure 1. is a diagram of the preferred method of employing the receiver; Fig. 2 is a central cross-section of a convenient form 20 of mounting the detector; and Fig. 3 is a diagram showing an alternative method of hooking the detector in the circuits.

Various detectors for wireless telegraphy have been employed, of which the essential 25 element was a joint between two electrodes which has the ability, in some way not now known, to indicate the presence of oscillating currents of very high frequency such as employed in wireless telegraphy signaling.

30 Some have attributed it to various crystal's thermo-electric action, and some have called the action "rectifying." All that is really known is that oscillating currents passing through a joint between certain electrodes, 35 makes its presence manifest by giving the effect of a current which can operate an indicator such as a telephone. This occurs in some cases in connection with a constantly flowing local current through the joint, and 40 in some cases without this auxiliary current. I have discovered that such a joint between the materials ferro-silicon and antimony has a very great advantage in being very steady, allowing a heavy pressure with perfect contact, being immune from disarrangement by static disturbances and not requiring delicate adjustment.

As illustrated in the drawing I prefer to use, in connection with the antenna circuit 4, 5, 6, a secondary circuit consisting of the coil 7 of a transformer, the detector 8, 9, battery 10, telephone 11 and condensers 12 and 13, one of which, 13, should be variable.

It will be understood that the battery is used with a variable potentiometer coil 14. The 55 oscillating current takes effect at the detector 8, 9, in such a way as to vary the current in the telephone 11 in approximate proportion to the energy of the received waves on the antenna 4.

60 The detector as shown, comprises a metal cup 15 containing a ferro-silicon block 8, which is in good contact with a piece of antimony 9, adjustably held by a spring arm 18 and screw 19. Both these latter are 65 pivoted on a bolt 20 carried by a pivoted arm 21 on a post 22, all the parts being mounted on a base 23 and provided with the usual binding post 24, 24^a. Thus the antimony point 9 may be moved to any part of 70 the ferro-silicon block 8 and the pressure varied by the screw 19 and spring 18. I find this instrument works best with a comparatively heavy pressure between the electrodes 8, 9; the antimony block 9 having a blunt 75 point and the ferro-silicon being in rough crystal form. Also I find the connection as shown in Fig. 1 to be the preferable form. In Fig. 3 however, I have shown another arrangement in which the condenser 16 is 80 placed differently from the condenser 12 of Fig. 1.

75 In practical use I have found this detector to be about as sensitive as the so-called perikon detector, and very free from disturbance and easy to adjust on account of the excellent contact between the electrodes.

Having thus described my invention and illustrated its use, what I claim is:

1. A detector for wireless telegraphy comprising a good contact joint between two electrodes of which one is antimony and the other ferro-silicon.

2. A detector for wireless telegraphy consisting essentially of ferro-silicon and antimony, and means for holding them in contact with adjustable pressure, substantially as described.

In testimony whereof I have hereunto signed my name in the presence of the two 100 subscribed witnesses.

WILLIAM E. BEAKES.
